UNITED STATES PATENT OFFICE.

ALLAN S. BARROWS, OF CHICAGO, ILLINOIS.

SHEET-METAL DOOR.

1,342,400.

Specification of Letters Patent.

Patented June 1, 1920.

Application filed March 28, 1919. Serial No. 285,851.

To all whom it may concern:

Be it known that I, ALLAN S. BARROWS, a citizen of the United States, residing at Chicago, in the county of Cook and State 5 of Illinois, have invented a certain new and useful Improvement in Sheet-Metal Doors, of which the following is a full, clear, concise, and exact description, reference being had to the accompanying drawings, forming 10 a part of this specification.

This invention relates to improvements in sheet metal doors.

In railway practice, much difficulty has been experienced heretofore in connection 15 with the side doors of box cars. The original form was, of course, the wood door which has proven entirely unsatisfactory for present day conditions because of its excessive weight, inflammability, liability to distortion and sagging, and liability to splintering and mutilation. As is well known, many attempts have been made by inventors and railroads to produce a satisfactory all-metal door to replace the wood doors, the 20 all-metal doors being intended for either wood box cars, combination wood and metal cars or all-metal cars. The attempts heretofore made to produce an all-metal door have divided themselves generally into two 25 classes,—one class comprising structures wherein a door frame is made from commercial or other suitable beams and sheet metal strips applied thereto, and the other, the doors formed of sheet metal of considerable 30 inherent strength and reinforced at different points by angle irons or Z-bars or the like applied thereto or riveted thereon.

With both types of metal doors above indicated, the weight is excessive, thus representing an unnecessary initial cost and also militating against the efficient operation of the cars which are thus compelled to carry an unnecessary dead weight. In addition, such doors have proven unsatisfactory in 45 that they sag, warp and become easily indented both at the margins and centrally from lateral shifting of the car loads. As understood by those skilled in the art, doors for box cars are required to undergo unusually severe strains, the doors being frequently pried open with claw bars and

closed in a similar manner; the doors are frequently left loose while the car is in transit thus causing the doors to be shunted with great force against the stops or door 55 frame; the car body weaves while traveling along the track, thus tending to distort the side walls of the car and the doors carried thereby; and in addition, the doors are required to withstand the lateral shocks or 60 thrusts imposed thereagainst due to shifting of the load while the car is in transit.

The object of my invention is to provide a sheet metal door particularly adapted for railway cars, which door is of maximum 65 strength per unit of weight; is strengthened with a minimum amount of metal in those points particularly subject to strains and in such manner as to most effectively resist the particular strains imposed upon the door at 70 the particular point; to provide a door of the character described which is free from the usual reinforcing angle irons, Z-bars, etc., and consequently of minimum weight; and to provide a door embodying the foregoing 75 characteristics which may be manufactured at comparatively small expense.

The invention furthermore consists in the improvements in the parts and devices herein shown, described and made the subject matter of claim.

In the drawing forming a part of this specification, Figure 1 is an elevational view of a sheet metal door embodying my improvements, the door being such as would be 85 adapted for the side door of a box car. Figs. 2 and 3 are sectional views of the door shown in Fig. 1 and taken on the lines 2—2 and 3—3 thereof respectively. Fig. 4 is a detail perspective of one of the reinforcing strips employed in the door shown in Fig. 1. Fig. 5 is a view similar to Fig. 1 illustrating a somewhat different embodiment of the invention, parts of the door being broken away to better accommodate 95 the view on the sheet. Fig. 6 is a detailed, sectional view taken substantially on the line 6—6 of Fig. 5. Fig. 7 is a detailed perspective of one of the reinforcing strips such as may be employed with the construction illustrated in Fig. 5. Fig. 8 is a view 100 similar to Fig. 6 but illustrating a some-

what different embodiment of the invention. Figs. 9, 10 and 11 are views similar to Figs. 1, 2 and 3, respectively, illustrating a still further embodiment of the invention.

5 Referring first to the construction illustrated in Figs. 1 to 4 inclusive, I have shown the door with the main or body portion thereof formed of three sheet metal panels or plates A, B and C. The panels A, B and 10 C have their adjacent horizontal edges overlapped as indicated at 20 and rigidly secured together either by spot-welding or by rivets as indicated at 21. The three panels when assembled as shown, form a rectangular door having of course vertical side edges and top and bottom edges.

In order to give the door the requisite strength, I employ what I may term "edge" corrugations 22, 23, 24 and 25 and additional 20 corrugations 26. The edge corrugations 22 and 23 extend or follow along the vertical edges of the door and are located relatively close thereto. In the instance shown in Figs. 1, 2 and 3, said corrugations 22 and 23 parallel 25 the edges of the door. Said corrugations 22 and 23 are extended from the main plane of the door to one side thereof, preferably the outer side of the door as the door would be viewed when in place on a car. Said corrugations 22 and 23 are made moderately deep so as to present the necessary rigidity against buckling or bending under forces applied perpendicular to the plane of the door.

35 The horizontal corrugations 26 are shown as extending continuously between the vertical corrugations 22 and 23 and merging with the latter as indicated at 27-27. The horizontal corrugations also provide great 40 strength against lateral bending or buckling of the door, and in addition where the same merge or coalesce with the edge corrugations 22 and 23, the latter are greatly strengthened against crushing under blows 45 applied horizontally and in planes parallel to the plane of the door, as will be appreciated from an inspection of Fig. 3.

Outside of the area defined by the edge corrugations 22, 23, 24 and 25, the door is 50 left with preferably relatively narrow flat marginal portions indicated at 28, 29, 30 and 31, respectively. Inasmuch as these marginal edge portions are subjected to forces which would ordinarily indent or distort this metal, as in opening or closing of the door with a claw bar, I provide the necessary strength by means of reinforcing sheet metal strips 32, 33, 34 and 35. The strip 32, which is on the right hand edge of 60 the door as viewed in Figs. 1 and 3, has its edge portion doubled over the main panel sheets of the door as indicated at 36 so that, in effect, a three-ply edge is obtained well adapted to resist indentation or crushing. 65 Said strip 32 is bridged over the correspond-

ing adjacent corrugation 22, as shown most clearly in Fig. 3, and along its inner portion said strip 32 is provided with scallops as indicated at 37-37 in Figs. 3 and 4. The scallops 37 are so spaced that they coincide 70 with the horizontal corrugations 26 and are pressed down into the latter. The strip 32 is preferably riveted to the main panel sheets of the door at intervals along the extreme marginal portion as indicated at 75 38 and also within the edge corrugation 22 between the horizontal corrugations as indicated at 39.

The opposed edge reinforcing strip 33 is applied similar to the strip 32 except that 80 instead of being doubled over the main sheets of the door, the latter and the strip 33 are together bent rearwardly as indicated at 40 and welded or riveted to thereby form a seal on that edge of the door. In the case 85 of the upper reinforcing strip 34, it is folded about the upper edge of the panel A as indicated at 41 and riveted to the main portion of the panel A within the corrugation 24 as indicated at 42. The lower reinforced 90 strip 35 bridges the corrugation 25 and is riveted to the panel C within the corrugation 25 as indicated at 43 and is preferably bent at right angles to the main plane of the door in conjunction with the lower edge 95 of the panel C as indicated at 44 to form another seal at the bottom of the door. The strip shown in Fig. 4 is that referenced 33 in Fig. 3 but as will be understood, the corresponding strip 32 is similarly scalloped 100 whereas the upper and lower reinforcing strips 34 and 35 are not scalloped.

At the upper corners of the door are shown plates 45-45 adapted to form suitable seats for roller hanger brackets for the 105 door as will be understood. In dotted lines as indicated at 46, I have indicated how bosses may be pressed into the metal to form suitable seats for receiving different types of roller-carrying brackets where the same cannot be applied on the flat corners as above indicated. In the lower corners of the door, plates 47 are or may be used corresponding to those shown in the upper corners and in this connection it will of 115 course be understood that where the reinforcing strips 32, 33, 34 and 35 meet at the corners of the door, they will be suitably matched and preferably the plates 45 and 47 will bridge (on the opposite sides of the 120 panels A and C) the meeting edges of said reinforcing strips to thereby secure a better union of the parts.

Of particular importance in my improved door is the construction of the so-called edge 125 corrugations in combination with the reinforcing strips which bridge said corrugations and are rigidly united to the main portions of the door sheets on opposite sides of said corrugations. With this arrange- 130

ment, I produce in effect what may be termed a "tube" which while made of comparatively light sheet metal is exceedingly strong against any of the forces which may be imposed thereon in any direction. This bracing of the edge corrugations and the additional backing or bracing afforded the corrugations 22 and 23 by the horizontal corrugations 26 renders the edges of the door extremely strong, well able to resist indentation, lateral pressure, buckling, sagging, weaving or distortion. It is also evident that the parts are such as may be readily manufactured as mostly die pressings and in actual practice I have found that doors made in accordance with my invention can be built from sheet metal of 3/32nds or 7/64ths thickness and successfully withstand the severe usage of railway service and furthermore that doors so manufactured are many pounds lighter than either all-wood or the former type of beam reinforced sheet metal door of either type hereinbefore referred to.

Referring to the construction illustrated in Figs. 5 and 6, I have shown the door in this instance formed of only two panels D and E. Edge corrugations are employed as in the doors shown in Fig. 1, that is, edge corrugations 122, 123, 124 and 125, and horizontal corrugations 126 merging with the side-edge corrugations 122 and 123. In addition, I employ a central, vertical corrugation 48 traversing or coalescing with the horizontal corrugations 126. This affords a somewhat greater strength against buckling or bending at the central areas of the door as will be understood. The edge corrugations are reinforced by means of reinforcing strips corresponding to those referenced 32, 33, 34 and 35 in the construction illustrated in Figs. 1, 2 and 3, and need not be here described.

In the construction shown in Figs. 5 and 6, however, I preferably employ an insert bridging reinforcing strip indicated at 49 in said figures, there being one of such insert strips 49 in each of the edge corrugations 122 and 123 where the panels D and E are overlapped and united. Such strips 49 are located within the corresponding corrugation so as to be clear of the top cover reinforcing strip 133 and the insert strips 49 are riveted to the panel sheets as indicated at 50—50. The insert strips 49 may be extended any desired length beyond the joint of the panels and will effectively strengthen the door at this point, as will be apparent.

In the construction shown in Figs. 5 and 6, instead of employing scalloped reinforcing strips such as 33 shown in Fig. 4, I employ corrugated strips as indicated at 133 in Figs. 6 and 7. In this construction, the strip is provided with a series of true corrugations 51 along its inner edge adapted to fit within

the horizontal corrugations 126 and the edge is left in a single plane as indicated at 52 in Fig. 6. A strip such as shown at 133 possesses certain advantages from a manufacturing standpoint over the strip 33 shown in Fig. 4 and also gives greater strength in the bracing of the edge corrugations since a better backing is afforded by the shallow corrugations 51 than by the tongues 37.

In Fig. 8 I have shown a modification of the reinforcing strip referenced 233, in this instance having formed it with a longitudinally extending corrugation 53 adapted to be fitted into the corresponding edge corrugation 223 of the main part of the door. These two parts may be riveted within the corrugations 53 and 223 and in this instance the strip 233 performs the function of the insert strip 49 shown in Figs. 6, as well as reinforcing the corrugation 223 against collapse although not quite as effectively as in the construction shown in Figs. 3 and 6.

Referring to the construction illustrated in Figs. 9, 10 and 11, I have shown the door as preferably formed of two panels F and G. In this instance, instead of extending the edge corrugations parallel to the edges of the door, the edge corrugations which I have designated 322 and 322^a; 323 and 323^a; 324 and 324^a; and 325 and 325^a follow or extend along the respective edges of the door at an angle thereto as clearly indicated in Fig. 9. Said edge corrugations, of course, remain sufficiently adjacent to the extreme edges of the doors to perform their necessary function but are preferably inclined slightly away from the edge of the door toward the median lines of the door. The marginal edge portions of the door are reinforced by multiple-plies of sheet metal as in the other figures and the reinforcing strips 332, 333, 334 and 335 are extended over and beyond the respective edge corrugations 322, etc., and riveted or otherwise rigidly united with the main panel sheets of the door on opposite sides of said edge corrugations to produce the same effect as in the constructions previously described. In the arrangement shown in Figs. 9, 10 and 11, horizontal corrugations may be employed within the area defined by the said edge corrugations and relatively short horizontal corrugations may be employed outside of the side edge corrugations 322, 322^a and 323 and 323^a, respectively, as indicated at 326^a. The arrangement of edge corrugations 322, etc., shown in Fig. 9 presents a slight advantage in that it affords a slightly greater resistance against sagging or distortion in the outline of the door. However, in view of greater economy in the manufacture, I prefer the construction illustrated in Figs. 1, 2 and 3.

Although I have herein shown and described what I now consider the preferred

manner of carrying out the invention, the same is merely illustrative and I contemplate all changes and modifications that come within the scope of the claims appended hereto.

I claim:

1. A door having the main portion thereof composed of a plurality of sheet metal panels, the adjacent edges of the panels being united, said door having corrugations extending along some of the edges thereof, additional strengthening indentations in the panel sheets, reinforcing strips secured to said main portion of the door along said edges, the strips and main portion of the door being united along the margins of the door outside of said corrugations and forming multiple-ply marginal edge sections, each strip being extended beyond its corresponding corrugation and united to the main portion of the door inside of the corrugation, whereby said corrugations are braced against collapse.
2. A door composed of a plurality of sheet metal panels and reinforcing strips, the panels being united to form the main portion of the door and having corrugations therein following along edges thereof, said reinforcing strips being each extended from one side to the other side of one of said corrugations and rigidly united to the main panel sheets on opposite sides of the corrugation to thereby brace the latter, the marginal edges of the door being composed of multiple-plies of sheet metal to thereby resist indentation.
3. A substantially rectangular door having the main portion thereof composed of a plurality of sheet metal panels having their adjacent edges united, said door having corrugations following along the two sides thereof, said panels being provided also with corrugations extending substantially transverse to the first named corrugations and merging with the latter to brace the same, and reinforcing strips applied to the marginal portions of the door to thereby form multi-ply edges, said reinforcing strips extending the full length of and out to the periphery of the respective edges.
4. A substantially rectangular door having the main portion thereof composed of a plurality of sheet metal panels having their adjacent edges united, said door having corrugations following along the two sides thereof, said panels being provided also with corrugations extending substantially transverse to the first named corrugations and merging with the latter to brace the same, and reinforcing strips applied to the marginal portions of the door to thereby form multi-ply edges, said reinforcing strips being extended beyond the first named corrugations and having portions pressed into said transverse corrugations,

the reinforcing strips being united to the main panel sheets on opposite sides of the first named corrugations.

5. A door having the main portion thereof composed of a plurality of sheet metal panels having their adjacent edges united, the door being of substantially rectangular formation and provided with a corrugation extending along and relatively adjacent to each of the four edges thereof, the panels being provided with integral indentations within the area defined by said corrugations, a reinforcing strip along each edge of the door, each strip being united to the main portion of the door on opposite sides of its corresponding corrugation to thereby brace the latter against collapse, said strips in conjunction with the main portion of the door forming multi-ply marginal edge sections to resist indentation.

6. A door of the character described composed of a plurality of sheet metal panels having adjacent edges overlapped and united throughout the length of the overlapped joint, said panels having corrugations therein extending transversely of the overlapped joint and disposed relatively adjacent the edges of the door, strips inserted within said corrugations and bridging the panel joints, the door having multi-ply marginal edge portions.

7. A door of the character described composed of a plurality of sheet metal panels having adjacent edges united and forming a door of substantially rectangular formation, said door having a corrugation following along each edge thereof, a reinforcing strip secured to the main portion of the door along each edge thereof, additional corrugations extending between and merging with the side edge corrugations of the door, said strips being extended over the respective adjacent edge corrugations and united to the main portions of the door on both sides of the respective edge corrugation, said strips in conjunction with the main panel sheets of the door forming multi-ply edges, the reinforcing strips applied to the side edges of the door having their inner portions indented within the transverse corrugations, said reinforcing strips preventing material from entering the respective edge corrugations.

8. As an article of manufacture, a sliding door composed of sheet metal and provided with edge corrugations therein located relatively close to the edges, said corrugations paralleling respective adjacent edges, the sheet metal being provided also with additional strengthening indentations within the boundaries of said edge corrugations, said door being formed with relatively narrow, flat marginal portions outside of said edge corrugations, each of said marginal portions being formed of the sheet

metal of the main part of the door and an extra reinforcing strip rigidly united to thereby produce multiple thicknesses of sheet metal in said marginal portions, said 5 corrugations and indentations serving to strengthen the door against strains, one ply of each of said marginal portions being extended over the corresponding adjacent edge corrugation and secured to the main portion 10 of the door within the boundary of the edge corrugations.

9. As an article of manufacture, a door having side edges, said door being composed of sheet metal and provided with outwardly 15 extending, hollow edge corrugations disposed adjacent to and paralleling said side edges of the door, the door being provided also with additional outwardly extending 20 integral strengthening depressions within the boundaries of the edge corrugations, said door having relatively narrow marginal portions disposed outside of said edge corrugations, some of said marginal portions comprising three plies of sheet metal 25 composed of the sheet metal forming the main part of the door and an extra reinforcing strip united by doubling the edge of one over the edge of the other, one of said plies of metal, along one side edge and on the 30 inner side of the door, being extended over and beyond the corresponding adjacent edge corrugation and secured to the main portion of the door within the boundary of the corresponding edge corrugation to 35 thereby brace and cover the latter and prevent articles on the inner side of the door from lodging in said edge corrugation when the door is in closed position.

10. As an article of manufacture, a door 40 of substantially rectangular form and adapted for use as a box car door, said door being composed of sheet metal and provided with edge corrugations therein located relatively close to each edge and paralleling the latter, the sheet metal of said 45 door being provided also with additional corrugations within the area defined by said edge corrugations, said additional corrugations including horizontal corrugations 50 merging at their ends with the vertical edge corrugations of the door, the door being formed with relatively narrow marginal portions outside of said edge corrugations, each of said marginal portions being composed 55 of a multiple of plies of sheet metal including the sheet metal forming the main part of the door and an additional reinforcing strip rigidly united, one of said plies of sheet metal along each vertical side of the 60 door being extended over the corresponding adjacent vertical edge corrugation and

depressed into said horizontal corrugations that merge with the vertical side edge corrugations, said extended plies covering the vertical edge corrugations and bracing the 65 latter.

11. As an article of manufacture, a door of the character described formed of sheet metal, said door having flat marginal portions composed of a multiple of plies of sheet metal consisting of the sheet metal forming the main part of the door and an additional reinforcing strip, said door being provided with strengthening indentations within the confines of said flat marginal portions, said indentations having portions thereof extending in proximity to said flat marginal portions, one of the plies of each of said marginal portions being extended inwardly beyond the ends of said 80 proximate portions of said indentations and secured to the sheet metal comprising the main part of the door at points inside of said ends of the indentations, whereby said indentations are braced against collapse and 85 the multiple-ply marginal portions adapted to resist indentation.

12. A substantially rectangular door having the main portion thereof composed of sheet metal, said door having corrugations following along the two sides thereof, said main portion of the door being provided with corrugations extending substantially transverse to the first named corrugations and merging with the latter to brace the 90 same, and reinforcing strips applied to the marginal portions of the door to thereby form multiple-ply edges, said reinforcing strips extending the full length of and out to the peripheries of the respective edges. 100

13. A substantially rectangular door having the main portion thereof composed of sheet metal, said door having corrugations following along the two sides thereof, said main portion of the door being also provided with a plurality of corrugations located within the area between said first named corrugations and extending at an angle to the latter and merging therewith at a plurality of spaced points intermediate 105 the top and bottom ends of said first named corrugations, and reinforcing strips applied to the marginal portions of the door to thereby form multiple-ply edges, said reinforcing strips extending the full length of 110 and out to the peripheries of the respective edges. 115

In witness that I claim the foregoing I have hereunto subscribed my name this 12th day of Mar., 1919.

ALLAN S. BARROWS.
